UNITED STATES PATENT OFFICE.

FRANZ OBELHARDT, OF FUERTH, GERMANY.

RAIL-JACK AND THE LIKE.

No. 812,080.

Specification of Letters Patent.

Patented Feb. 6, 1906.

Application filed February 17, 1905. Serial No. 246,118.

To all whom it may concern:

Be it known that I, FRANZ OBELHARDT, station-master, (whose post-office address is No. 8 Gebhardtstrasse, Fuerth, Bavaria, in the Empire of Germany,) have invented certain new and useful Improvements in or Relating to Rail-Jacks and the Like; and I do hereby declare the following to be a full, clear, and exact description of the invention, such as will enable others skilled in the art to which it appertains to make and use the same.

The invention relates to an improved lifting-jack especially adapted for lifting railroad-iron, such as rails and the like, and has for its object the provision of a lifting member which after performing its function may be readily disengaged from the rail or other part while the same is suspended.

To this end the invention consists of a supporting-frame provided with suitable operating means, together with a rack or the like, adapted by said means to be raised and lowered, said rack carrying a hook-shaped member mounted to swing and to normally occupy a lifting or engaging position, there being also provided a lever and lifting-chain for swinging the hook into a non-engaging position.

In the drawings, Figure 1 illustrates one embodiment of my invention, showing the same in connection with a railroad-rail. Fig. 2 is a detail view of the hook and rack-bar.

There is shown a main supporting structure comprising standards *h* and a housing *h'*. A bar *d*, provided with teeth and having in its upper end an eye, travels vertically through the casing and is operatively engaged therein by a train of gears, as shown, which are operated by a crank *j* and a pawl and ratchet *j'* and *j''*. The hook *b* is pivotally secured to the lower end of the rack-bar *d*, preferably by means of links *a* and pins *c c'* in a manner to maintain said hook in a normally vertical or lifting position and permit the same to be swung laterally into an inoperative position. The hook *b* is provided with a recess *g*, adapted to engage a projection or angular fish or rib which may be provided to prevent the

rail from slipping off the hook. The means for swinging said hook in the manner described consists of a hook-detaching lever *e*, 50 pivotally mounted upon one of the standards *h* and provided between its ends with an opening or slot through which a lifting-chain is inserted, the latter having a ring *i* to prevent the same from being entirely withdrawn 55 from engagement with the lever. The opposite end of said chain is secured to the hook *b* in any suitable manner.

In the operation of lifting a railroad-rail or the like the hook *b* is engaged therewith, as 60 shown in Fig. 1, and the crank *j* is turned to impart to the rack-bar *d* a vertical movement through the gearing, as will be seen by reference to Fig. 1. When it is desired to disengage the hook from the rail, the operator grasps the lever *e* and raises it to the position shown in dotted lines, thereby serving to swing the hook laterally and disengage it from the rail, as shown. The chain is secured to the lever in a manner to permit the operator to grasp the ring *i* and adjust the hook *b* to any angular position in the operation of engaging it with the object to be raised. This feature is of great practical advantage. When there is no load imposed upon the hook, it 75 can be far more conveniently swung or adjusted by means of the chain than by raising the lever *e*. On the other hand, when a load is imposed upon the hook the operator gains in leverage by using the lever *e*. 80

What I claim, and desire to secure by Letters Patent, is—

A lifting-jack comprising an operating gearing, a hook operatively connected therewith, the hook portion being mounted to 85 swing, a hook-detaching lever, and a chain secured to said hook and slidably connected with said lever.

In testimony whereof I affix my signature in presence of two witnesses.

FRANZ OBELHARDT.
